UNITED STATES PATENT OFFICE

2,134,573

ELECTRIC CIRCUIT BREAKER

William E. Paul, Schenectady, N. Y., assignor to
 General Electric Company, a corporation of
 New York

Application May 17, 1938, Serial No. 208,392

14 Claims. (Cl. 200—150)

My invention relates to electric circuit breakers of the fluid blast type wherein arc pressure generated upon opening of the circuit is utilized to produce an arc-extinguishing fluid blast.

Heretofore, difficulty has been encountered in designing a circuit breaker of the aforesaid type to interrupt satisfactorily currents ranging from a few amperes to those of short circuit proportions. This is due to the great variation of arc pressure at different current values for a given length of arc, such as in the case of a high voltage power circuit breaker of the well-known oil blast type. In order to produce an effective arc-interrupting blast, the arc pressure at low currents must be utilized to maximum advantage. At high currents, however, the pressure may be dangerously high unless the arc chamber is instantly vented or the arc is restricted as to length.

Various solutions to this problem have been proposed including control initiated by the arc-generated pressure. However, in view of the high opening speeds now required in practice, it is highly desirable that the arc pressure be anticipated rather than allowed to develop before initiation of control. Other methods have also been proposed such as, for example, short circuiting part of the arc in case of heavy currents, and conversely looping and lengthening the arc in the case of weak currents. However, these methods are not always practical and satisfactory for particular operating requirements.

In accordance with my invention excessively high arc pressures are anticipated by electro-magnetic means responsive to the magnitude of the current to be interrupted. More particularly, the circuit breaker functions normally at low current values for developing sufficient arc pressure to interrupt arcing, whereas at high or short circuit currents the pressure-generating arc is automatically shortened by utilizing electromagnetic forces in the circuit that is to be interrupted for moving an electric conductor, which may form part of the contact structure, with respect to the arc path. With this arrangement excessively high arc pressures are anticipated since the control is independent of the time of contact separation and solely dependent on the magnitude of the current to be interrupted.

My invention will be more fully set forth in the following description referring to the accompanying drawings, and the features of novelty which characterize my invention will be pointed out with particularity in the claims annexed to and forming a part of this specification.

Referring to the drawings, Fig. 1 is an eleva-

tional view, partly in section, of an electric circuit breaker of the oil blast type embodying my invention; Fig. 2 is an enlarged sectional view of the arc control contact structure shown by Fig. 1; Fig. 3 is an elevational view in perspective, partly in section, illustrating another form of my invention; Fig. 4 illustrates an arc control contact structure particularly suitable for circuit breakers having a wide interrupting capacity, Fig. 5 is a fragmentary view of another form of arc control device embodying my invention, and Fig. 6 is a partly sectional view of an arc control device employing the induction principle also embodying my invention.

The circuit breaker illustrated by Fig. 1 is of the well-known oil blast type and comprises a steel pressure confining casing 1 within which is mounted relatively movable contact structure including a fixed contact structure 2, movable contact 3, and intermediate gate contacts 4. The contact structure is oil-immersed as indicated. The intermediate contacts are mounted on an insulating baffle structure 5 forming within the casing 1 a lower arc chamber 6 and an upper exhaust chamber 7. The baffle structure 5 is provided with a transverse passage 8 interconnecting the chambers 6 and 7 and also intersecting a longitudinal bore 9 through which the movable rod contact 3 operates. The conducting gate contacts 4 are normally biased by springs 4' to close the bore 9 at its lower end when the contact 3 has moved past the gates toward the open circuit position. In the closing operation the contact 3 simply biases the gates apart and moves through the bore 9 into the arc chamber 6 to engage the fixed contact structure 2. The circuit breaker structure so far described forms no part of my present invention and is described in detail and claimed in my U. S. Patent No. 1,947,224 for Circuit interrupting apparatus, granted February 13, 1934.

In the operation of this breaker, a pressure-generating arc is formed between the fixed contact structure 2 and the intermediate or gate contacts 4, the pressure generated within the oil-filled chamber 6 being utilized to create an arc-extinguishing blast through the passage 8 transversely of the arc between the gate and movable contacts when the contact structure is in the position illustrated.

Where the length of the pressure-generating arc in the chamber 6 is substantially fixed, it will be apparent that although the breaker may work well on low or medium currents, for example, the pressure generated in the case of

50

55

short circuits may be so great as to damage or destroy the breaker.

For the purpose of anticipating these excessive pressures, I utilize electromagnetic forces of the 5 circuit to be interrupted to shorten automatically the pressure-generating arc to an extent depending on the magnitude of the arc current. To this end the fixed contact structure 2 is provided with an arcing member, such as a ring or bell 10 that is relatively movable with respect to the fixed structure along the path of the pressure-generating arc.

Referring more particularly to Fig. 2, which 15 illustrates the fixed contact structure 2 in section and in greater detail, the main contact support comprises a conducting frame 11 that is suitably expanded at its lower end, as illustrated in Fig. 1, into good electrical contact with the terminal portion 1' of the steel casing 1. The 20 support 11 can be generally in the form of a cylinder open at opposite ends and has mounted thereon an arcing ring 10 which is provided with a cylindrical depending extension 12 serving as a carrier for the segmental contacts 13 coacting 25 with the rod contact 3. The segmental contacts 13 are suitably biased in a well-known manner into contact with the rod 3 by garter springs 14 and are electrically insulated at 15 and 16 from the conducting carrier 12. The segments, however, 30 are electrically connected by flexible leads 17 to the lower end only of the carrier for the purpose presently described.

The arcing ring 10 and carrier 12 constitute 35 a unit that is adapted for relative movement with respect to the frame 11. The unit is normally biased to its position shown within the frame by a helical spring 18 seated between an annular insulating abutment 19 secured to the frame 11 and an insulating collar 20 secured to the lower 40 end of the carrier 12. The carrier unit is limited as to vertical movement by a lower abutment 21 and an upper abutment 22 forming part of the frame coacting with the insulating collar 20. The conducting frame 11 and the arcing ring 10 45 are electrically interconnected by looped flexible conductors 23 designed to permit movement of the arcing ring between the upper and lower limits previously described.

In the closed circuit position shown (Fig. 2), 50 the circuit from the terminal of the movable contact 3 to the terminal formed by the casing 1 is completed through the rod contact 3, segmental contacts 13, electrical connections 17, conducting carrier 12 and arcing ring 10, conducting loops 23, and conducting frame 11. It 55 will therefore be noted that the circuit includes a loop at the conductors 23 that can expand, carrying with it the arcing ring 10, when current of predetermined magnitude flows through the 60 circuit. Since the arcing ring 10 is at all times electrically connected to the fixed contact structure 2, movement of the carrier 12 upwardly against the bias of spring 18 in response to electromagnetic 65 force of large currents automatically shortens the arc distance between the intermediate contacts 4 and the fixed structure 2. The pressure-generating arc is correspondingly decreased in length, and it will be apparent that the spring tension at 18 and the design of the conducting loops 23 70 may be so chosen that the pressure-generating arc has a definite and predetermined length for a given current flowing through the breaker. With this arrangement the breaker can be designed so that the normal arc length at low currents 75 is sufficient for arc interruption, and in

the case of higher currents the arc can be automatically shortened to a point comparatively close to the intermediate contact structure 4 as illustrated in the dotted line position shown in Fig. 1.

It will also be noted that the circuit includes another loop formed by the segmental contacts 13, flexible conductors 17 and the cylindrical carrier 12. In this case the expanding forces of the loop tend, in the case of heavy currents, to bias the segments 13 into good contact engagement with the rod contact 3 for minimizing heating due to contact resistance. This is an obvious advantage, particularly where the normal current rating of the breaker is high. In the case 15 of arc interruption the added friction between the segments 13 and rod contact 3 may cause the rod contact to carry with it the arc control unit. However, when its upper limit is reached the contacts separate and if the current is sufficiently high, the unit will remain in its short-arc position; otherwise, the spring 18 will retract the unit to an extent depending on the arc current. Therefore, the arc pressure is anticipated 20 in any case.

Referring to Fig. 3 there is illustrated a comparatively-compact fixed contact unit arranged generally to function in the manner of Fig. 1. In this latter arrangement the circuit breaker structure is essentially the same and the fixed 25 contact structure likewise has several similar features. The contact support as in the previous case is expanded at 25, such as by a pin wedge at 28', into good contact engagement with the steel casing 1, and an arcing bell 26 having a 30 depending cylindrical carrier 27 for the contact segments (not shown) is mounted, as in the case of Fig. 2, for relative movement in the frame 25. Secured and electrically connected at 28 to the conducting frame 25 is a discontinuous ring 28 35 also connected at 30 by a flexible looped conductor to a counter or second discontinuous ring 28'. The ring 28' is secured and electrically connected to the bell 26 only at 31 so that the ring-like conductors 28 and 28' together with the 40 flexible conductor 30, form a loop that is bent around the longitudinal axis of the arcing bell 26.

The arcing bell 26 and carrier 27 are suitably biased by a spring (not shown) to a retracted position within the frame as in the case of Fig. 2, 45 the spring being omitted in the interest of clearness.

In the operation of the device, the pressure-generating arc, as in the previous case, is formed 50 between the arcing bell 26 and the intermediate contact structure 4. The path of the arc current through the fixed contact structure is as indicated by the directional arrows, the current flowing from the arcing bell 26 through the ring 28' in a clockwise direction as viewed, and through 55 the flexible conductor 30 in counterclockwise direction through the counter ring 28 which is mechanically and electrically connected to the fixed 60 conducting contact support 25. The segmental 65 contacts (not shown) can if desired be connected in the circuit in the manner shown in Fig. 2.

When the breaker is opened the electromagnetic repulsion between the rings 28 and 28' due 70 to the opposing directions of the current paths causes extension of the arcing unit (26, 28' and 27) in an upward direction tending to shorten the arc to an extent depending on the magnitude of the arc current. This arrangement is obviously more compact than that of Fig. 1 since the 75 loop for utilizing the electromagnetic forces of

the circuit is concentrically disposed with respect to the arc and in effect bent back upon itself, as contrasted with the laterally extending loops 23 of Figs. 1 and 2.

5 The arrangement shown by Fig. 4 is particularly adapted to utilize to the maximum extent the electromagnetic forces involved in a circuit loop associated with the movable arcing member. To this end the relatively movable arcing member 34, which may also constitute the contact structure, is electrically connected at 35 to an insulated conductor 36 that is normally arranged in a flattened double loop and connected at its other terminal at 37 to the conducting 10 expanding ring 37' corresponding in function to the expanding ring 25 of Fig. 3. The movable arcing member 34, which can be suitably formed as a socket contact, for example, for coacting with the contact tip of the movable rod 3 is mounted for limited reciprocal movement with 15 respect to an insulating cylinder 38 having a central bore 38' within which a guide extension 39 of the movable member 34 is disposed. The insulating cylinder 38 is fixed within the expanding ring 37'. The extension 39 is resiliently biased by a helical spring 39' toward the retracted position shown. Accordingly, when current traverses the breaker the insulated looped conductor 36, which is suitably secured at one 20 point to the movable arcing element 34, such as by a clip member 36', tends to expand so as to form a circle. Expansion of the loop is opposed by the spring 39' which is selected as in the previous case in accordance with the operating requirements of the breaker.

25 The insulated conductor 36 can obviously form any desired number of loops in order to meet the particular design requirements of the breaker. For example, where lateral space is restricted, the number of coils can be increased. The conductor loops are also preferably designed so that the arcing member 34 is at the position of minimum arc length when the loop is in the form of a substantially complete circle. With this arrangement the electromagnetic forces acting on the loops are substantially dissipated in hoop tension and the movable arcing unit is accordingly not subjected to high mechanical stresses when in the position of minimum arc length. 30 When the circuit is interrupted the spring 39' returns the arcing member 34 to its initial retracted position where it remains in the case of small current interruptions.

35 In the arc control devices so far described, it should be noted that the electromagnetic forces tending to influence the position of the arcing member are present before the arc is actually formed. Accordingly, there is a tendency to initiate and accelerate the movement of the 40 arcing member before the arc is drawn. This is particularly important in the case of short circuit currents since the pressure generated within the oil by the arc might otherwise retard the arc-regulating operation of the arcing member. 45 This is overcome according to my invention by applying the electromagnetic forces to the arcing member so that it moves along with the movable contact until it reaches its regulating position as determined by the magnitude of the arc current. 50 In other words, the control anticipates excessive arc pressure due to a long, heavy current arc.

55 Fig. 5 illustrates a simplified arrangement wherein the fixed segmental contacts 40 coact with the rod contact 3 in the manner above described, the segmental contacts being suitably

mounted within a conducting support 41 that is electrically connected to a terminal of the breaker. The relatively movable arcing ring 42 is in the present instance pivotally mounted with respect to the support 41 by means of an arm 43 pivotally connected at 44 to a conducting extension 45 of the contact carrier. A spring 46 functions to keep the arcing ring normally in the retracted position shown, and a stop member 45' fixed to the support 45 serves to limit movement 10 in the opposite direction.

15 The conducting loop in the present instance for controlling the position of the arcing ring is formed by the conducting members 43 and 45 and to this end the aforesaid members are electrically connected by a flexible conductor at 47 adjacent the pivot 44 and are provided with an insulating spacer 48 for preventing short circuiting of the loop. The operation is believed to be apparent from the above description, the arc 20 current after transferring to the arcing ring 42 traversing the loop 43-45 to control the position of the arcing ring in accordance with the magnitude of the arc current. This design is comparatively simple in that the breaker in the 25 closed circuit position utilizes simply the conventional contact structure, the arcing ring functioning only upon opening of the circuit on heavy or short circuit currents. The relation between arc length and arc current can readily 30 be chosen by suitable adjustment of the spring tension at 46, and also by changing the dimensions of the loop 43-45.

35 In the arrangement shown by Fig. 6, the induction principle is employed for the purpose of simplifying the structure in certain cases and for anticipating high arc pressures in the manner previously referred to. To this end the magnetic force for moving the arcing member for decreasing the arc length is obtained from induced current instead of from a direct series connection.

40 Referring more particularly to the structure disclosed, the expanding member or ring 50 for securing and electrically connecting the contact structure to the lower part of the breaker casing 45 as in the preceding cases, is electrically connected through a series coil 51 to the fixed contact structure 52 which coacts with the movable rod contact 3. In the present case the fixed contact 52 is mounted within a stationary insulating cylinder 53 that is secured to the switch casing in any suitable manner, the cylinder being provided with lateral flanges 53' for positioning the arc control means.

45 The movable arcing member for decreasing the arc length in accordance with the magnitude of the current comprises in the present instance a conducting sleeve 54 of copper or the like mounted around and concentrically of the insulating cylinder 53. The sleeve 54 is biased by a spring 55 seated on the upper flange 53' of the fixed cylinder 53 toward a retracted position with respect to the arc path, and as shown is in the maximum arc length position. For the purpose of relieving gas pressures and eliminating piston effect, the 55 sleeve 54 is provided with apertures 54'.

50 When current of predetermined magnitude traverses the series coil 51 current is induced in the conducting ring 54, which forms in effect a short-circuited secondary of a transformer, so 55 that the primary and induced currents flowing in opposite directions establish a repellent force tending to raise the ring 54 against the bias of spring 55 to the arc-controlling position required. The arc is thereby bridged in part, the total arc

length then comprising the two short arcs formed between the rod 3 and ring 54, and the ring 54 and fixed contact 52.

Accordingly, the arc pressure is anticipated even before separation of the contacts, since the movement of the arcing member is entirely independent of the movable contact structure. A particular advantage of this arrangement resides in the fact that flexible conductors, or "pigtails", connected to the movable arcing member are unnecessary but may be used if desired.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States, is:

20 1. An electric circuit breaker of the fluid blast type comprising separable contact structure between which an arc is formed upon opening of the circuit, a movable arcing member and electromagnetic means controlled by the arc current for moving said arcing member with respect to the arc path so as to decrease the length of said arc to an extent depending on the magnitude of the arc current.

25 2. An electric circuit breaker of the arc-generated fluid blast type comprising separable contact structure between which a pressure-generating arc is formed upon opening of the circuit, an arcing member movable with respect to one of the contacts, and electromagnetic means controlled by the arc current for causing movement of said arcing member into the arc path so as to decrease the length of said arc to an extent depending on the magnitude of the arc current.

30 3. An electric circuit breaker of the arc-generated fluid blast type comprising a pair of relatively movable contacts between which an arc is formed upon opening of the circuit, contact structure positioned intermediate said contacts in the open circuit position thereof, an arcing member associated with one of said contacts, said arcing member being movable beyond said contact toward said intermediate contact structure and into the arc path, and electromagnetic means controlled by the arc current for causing movement of said arcing member so as to decrease the length of the arc between said arcing member and intermediate contact structure to an extent depending on the magnitude of the arc current.

35 4. An electric circuit breaker of the arc-generated fluid blast type comprising separable contact structures between which an arc is formed upon opening of the circuit, an arcing member electrically connected to and movable with respect to one of the contacts and electromagnetic means controlled by the arc current prior to separation of said contact structure for moving said arcing member with respect to the arc path so as to decrease the length of said arc to an extent depending on the magnitude of the arc current, said electromagnetic means tending to initiate the movement of said arcing member at the instant overload occurs whereby generation of excessive arc pressure is anticipated.

40 5. An electric circuit breaker of the arc-generated fluid blast type comprising a fixed contact and a coacting movable contact, an arcing member mounted on said fixed contact for reciprocal rectilinear movement with respect thereto, said arcing member being adapted to extend beyond said fixed contact into the arc path, means biasing

said member towards a retracted position with respect to said arc path and flexible conducting means interconnecting said member and fixed contact forming a loop for moving said arcing member into the arc path to an extent depending on the magnitude of the arc current. 5

6. An electric circuit breaker of the fluid blast type comprising relatively fixed, movable and intermediate contact structures arranged so that the arc pressure generated between said intermediate structure and one of said other structures tends to interrupt the circuit, and arc control means for the pressure generating arc including an arcing member movable with respect to one of said contact structures into the arc path, and electromagnetic means for biasing said arcing member into the arc path for shortening said arc to an extent depending on the magnitude of the arc current. 10 15

7. An electric circuit breaker of the arc-generated fluid blast type comprising a fixed contact and a relatively movable contact between which a pressure-generating arc is formed upon separation of said contacts, arc control means mounted for relative movement with respect to said fixed contact comprising an arcing ring movable between said fixed contact and a position beyond the same into the arc path, means biasing said arcing ring towards a retracted position with respect to said path, contact means for coacting with said movable contact carried by and movable with said arcing member, and flexible conducting means inter-connecting said fixed contact structure and said arcing ring, said conducting means being formed as a loop so that the electromagnetic 35 forces of the arc current tend to bias said arcing ring into the arc path to an extent depending on the magnitude of the arc current. 20 25 30

8. An electric circuit breaker of the arc-generated fluid blast type comprising fixed contact structure and a coacting movable contact, arc control structure mounted for relative movement with respect to said fixed contact structure comprising an arcing ring adapted to coact with said movable contact, a contact carrier secured to and depending from said arcing ring, a plurality of contact elements mounted in said carrier for engagement with said movable contact, means electrically connecting said contact elements to said carrier only at one end thereof, means electrically connecting the opposite end of said carrier at said arcing ring to said fixed contact structure, said means forming a loop arranged so that said arcing ring is biased into the arc path to an extent depending on the magnitude of the arc current traversing said loop, said contact elements being likewise biased into contact engagement with said movable contact in a similar manner, and spring means for biasing said arcing ring and contact carrier towards a retracted position with respect to said arc path, 45 50 55

9. An electric circuit breaker of the arc-generated fluid blast type comprising fixed and movable contact structures, arc control means associated with said fixed structure including a 60 conducting member in the form of a discontinuous ring, said ring being electrically and rigidly connected at one end to said fixed structure, a relatively movable discontinuous ring generally similar to said first ring in superposed position 70 with respect to said first ring, flexible conducting means interconnecting the free end of said first ring and one end of said second ring, contact means including an arcing member mounted for movement with said second ring, said 75

second ring and arcing member being electrically connected at another end of said ring so that arc current flowing from said arcing member to said fixed contact structure traverses said rings in opposite directions whereby said arcing member is biased into the arc path to an extent depending on the magnitude of the arc current, and resilient means for biasing in the opposite direction said arcing member.

10. An electric circuit breaker of the arc-generated fluid blast type comprising relatively movable contact structure between which a pressure-generating arc is formed upon separation of said contact structure, arc control means associated with one of said contact structures comprising an arcing member adapted to move into the path of said arc for decreasing the length thereof, and electromagnetic means for controlling the position of said arcing member in said path to an extent depending on the magnitude of the arc current comprising conducting means interconnecting said contact structure and said arcing member, said conducting means forming a current path in the shape of a compressed loop that is positioned substantially concentrically with respect to said arcing member.

11. An electric circuit breaker of the arc-generated fluid blast type comprising relatively movable contacts between which a pressure-generating arc is formed upon separation thereof, one of said contacts including a relatively movable arcing member adapted to move into the arc path for decreasing the length of said arc, and a flexible conductor interconnecting said contact and arcing member, said conductor being formed as a coil so that arc current traversing said conductor tends to move said arcing member into the arc path to an extent depending on the magnitude of the arc current whereby the minimum arc length position is attained when said conductor assumes a generally circular form.

12. An electric circuit breaker of the arc-generated fluid blast type comprising fixed and movable contact structures, arc control means mounted for relative movement with respect to

said fixed structure comprising an arcing member, a flexible conductor normally formed as a compressed coil having a plurality of turns electrically interconnecting said fixed structure and arcing member, said coil being mechanically connected at one terminal to said arcing member whereby expansion of said coil due to passage of arc current therethrough tends to move said arcing member into the path of the arc for decreasing the length thereof, and means resiliently biasing said arcing member in the opposite direction, the minimum arc length position of said arcing member being determined by the fully extended position of said coil whereby the electromagnetic stresses at high currents are substantially dissipated in hoop tension.

13. An electric circuit breaker of the fluid blast type comprising separable contact structure between which a pressure-generating arc is formed upon opening of the circuit, and arc control means associated with one part of said contact structure including a conducting arcing member movable with respect to said part into the arc path, means for resiliently biasing said member towards a retracted position with respect to said arc path, and means traversed by the arc current related to said arcing member so that said arcing member is repelled by magnetic forces into the arc path to an extent depending on the magnitude of said arc current.

14. An electric circuit breaker of the fluid blast type comprising separable contact structure between which a pressure-generating arc is formed upon opening of the circuit, a movable arcing member forming a short-circuited conductor, means resiliently biasing said arcing member toward a retracted position with respect to the arc path, and means traversed by the arc current associated with said contact and inductively related to said arcing member, said arcing member being repelled into the arc path by the resulting magnetic forces to decrease the length of the arc to an extent depending on the magnitude of the arc current.

WILLIAM E. PAUL. 45
